UNITED STATES PATENT OFFICE

FLETCHER D. GRUND, OF WESTON, OHIO, ASSIGNOR TO THE AMERICAN SWISS COMPANY, OF TOLEDO, OHIO, A CORPORATION OF OHIO

DOOR LATCH

Application filed October 21, 1926. Serial No. 143,028.

This invention relates to door latches of the type commonly used on automobiles.

An object of this invention is to provide a door latch which is sturdy in construction, reliable in operation, and inexpensive to manufacture.

Another object of this invention is to produce a door lock of the sliding bolt type having a dogging member which is slidable in a plane parallel to the bolt for preventing withdrawal of the bolt by manipulation of the outside retracting means.

Other objects will appear as the description proceeds.

15 In one aspect, this invention provides a sliding dogging member movable in a plane parallel to the movement of the sliding bolt for preventing manipulation of the outside retracting means. The dogging member may 20 be actuated to dogging position by actuation of the inside retracting means in a direction opposite to that of retracting the bolt. It has been found that a sliding dogging member mounted in the above manner lends 25 itself admirably to use in automobile doors because a compact construction is produced which occupies a minimum amount of space. Furthermore, this construction may be cheaply manufactured in large quantities so that 30 the unit may be sold at a price lower than any similar lock on the market, of which I am aware.

The invention is shown by way of illustration in the accompanying drawings, in which:

35 Fig. 1 is an elevation of a remote control door lock of the pull type, with the cover plate removed; Fig. 2 is a top edge view of the lock shown in Fig. 1; Fig. 3 is a section on the line 3—3 of Fig. 1; Fig. 4 is an elevation of a remote control latch of the rotary type, embodying the invention; Fig. 5 is a top edge view of the lock shown in Fig. 4; Fig. 6 is a section on the line 6—6 of Fig. 4; Fig. 7 is an elevation of another form of latch embodying the invention; Fig. 8 is a top edge view of the latch shown in Fig. 7; Fig. 9 is a section on the line 9—9 of Fig. 7; Fig. 10 is an elevation of another form of latch similar to that shown in Figs. 7 to 9, embodying

the invention; and Fig. 11 is a bottom edge view of the latch shown in Fig. 10.

The illustrated embodiment of the invention shown in Figs. 1 to 3, comprises a back plate 1 having a flanged end 2 through which the outer end portion of a bolt 3 is guided. The rear portion of the bolt 3 is guided by lugs 4 which project outwardly from the back plate 1. The bolt 3 is formed on opposite sides with grooves 5, the ends of which engage the lugs 4 which limit the movement of the bolt in opposite direction. For yieldingly holding the bolt 3 in operative or extended position, a coil spring 6 has one end fixed to the back plate and the free end thereof bears 65 against an abutment 7 on the bolt.

In order to retract the bolt 3 from the inside of the automobile, a plate 8 is provided in horizontally spaced relation to the plate 1, and a lever 9 is pivotally connected at its 70 lower portion to the plate 8 by a stud 10. Formed in the lever 9 intermediate the ends is a vertically elongate slot 11 into which a pin 12 projects. The pin 12 is carried by a horizontally disposed link 13 which has 75 a horizontal elongate slot 14 intermediate its ends. Projecting into the slot 14 is a stud 15 which is fixed to the bolt 3 so that by swinging the lever 9 in a clockwise direction the outer end of the slot 14 will engage 80 the stud 15, and retract the bolt 3 against the tension of the coil spring 6.

In order to retract the bolt 3 from the outside of the automobile, a hub 16 is rotatably mounted on the back plate 1, and a 85 shaft 17 projects into the squared opening 18 in the hub. By means of a handle secured to the outer end of the shaft 17, the hub may be rotated. Projecting from the hub 16 is an arm 19 engageable with an extension 20 of 90 the bolt 3, so that by rotating the hub in a clockwise direction (Fig. 1) it will be seen that the bolt 3 may be retracted. This form of retracting means is usually termed a roll back.

95 In accordance with the present invention, a sliding dogging member or pawl 21 is employed for movement to a position to prevent retraction of the bolt by the roll back. The dogging member 21 is disposed in a plane 100

parallel to the plane of movement of the bolt 3. It will be observed that this dogging member is arranged in close relation to the bolt so that a compact arrangement is provided. As shown, this member is mounted for horizontal sliding movement and the rear portion of this member is guided between the upper lug 4 and a lug 22 projecting from the back plate 1. The forward end portion 10 may rest upon and be guided by the forward end portion of the bolt 3, although this arrangement is not always desirable. The forward end portion of the dogging member 21 is adapted to be extended into the path of movement of a lug 23 projecting from the hub 16. When the dogging member is moved to dogging position, operation of the roll back is positively prevented.

Intermediate the ends of the dogging member 21 is formed a horizontal elongate slot 24 into which a guiding stud projects from the plate 1. It will thus be seen that movement of the dogging member 21 is guided by the lug 25, slot 24, lugs 4 and 22, and, under some circumstances, the upper edge of the locking bolt 3. Formed in the lower portion of the dogging member 21 is a relatively short horizontal elongate slot 26 into which extends a pin 27 on the connecting link 13.

30 In the operation of the above described latch, when the lever arm 9 is rocked in a clockwise direction (Fig. 1), the pin 27 first engages the inner end of the slot 26, and retracts the dogging member 21 from locking position. Further movement of the lever arm 9 brings the outer end of the elongate slot 14 into engagement with the stud 15, and thereafter the bolt 3 is retracted. By this arrangement movement of the lever arm 9 to the right first retracts the dogging member 21, and subsequent to this operation, the bolt 3 is withdrawn.

To move the dogging member 21 to locking position so that operation of the outside reTRACTING means is prevented, the lever arm 9 is moved to the left in a counter clockwise direction (Fig. 1) to bring the pin 27 first into engagement with the outer end of the slot 26, and further movement serves to slide the dogging member 21 horizontally to the left into dogging position. It will thus be seen that slight movement of the lever arm 9 to the left operates positively to actuate the dogging member 21 to dogging position. The slot and pin connecting between the lever arm 9 and link 13 enables the link 13 to move horizontally.

The above described latch is commercially termed a remote control latch, and is primarily designed for use in connection with relatively wide automobile doors where it is desired to have the control spaced a considerable distance from the latching mechanism so that the bolt may be conveniently reTRACTED without the operator assuming an un-

comfortable position. The above described arrangement is also known as a pull type of latch in which a lever is employed for reTRACTING the bolt.

A further type of the remote control is shown in Figs. 4 to 6. This arrangement is quite similar to that described in connection with the construction shown in Figs. 1 to 3. As shown in Fig. 4, an arm 28 is pivoted at 29 to the connecting link 13^a. The arm 28 projects from a hub 30 which is rotatably mounted on the plate 8^a. Secured for rotation with the hub 30 is a shaft 31 having squared end portion (Fig. 5) to receive a suitable handle. A bearing member 32 for the shaft 31 is secured to the opposite side of the plate 8^a.

In this construction it will be seen that by rotation of the shaft 31 in a counter clockwise direction, (Fig. 4) the bolt may be reTRACTED, subsequent to the withdrawal of the dogging member from latching position. Rotation of the shaft 31 in a clockwise direction moves the dogging member to latching position. As the remainder of this construction is the same as that above described, further description will not be given.

In the form of the invention shown in Figs. 7 to 9, inclusive, the bolt 3^b projects through a flange 2^b on the back plate 1^b as in the forms above described. The rear end portion of the bolt is guided by lugs 4^b projecting outwardly from the back plate 1^b and a coiled spring 6^b serves to hold the bolt 3^b projected. The bolt 3^b is formed with a horizontal elongate slot 33 having an outwardly extending lug 34 at the inner end thereof. The inner part of the dogging member 35 is depressed to provide a portion 36 which protrudes into the slot 33, and the end of this member is turned outwardly to form an abutment 38 which is adapted to engage the projection 34.

For actuating the dogging member 35 and reTRACTING the bolt 3^b, an arm 39 fixed to a shaft 40 extends upwardly and the outer portion lies over the depressed portion 36. Formed in the arm 39 is a longitudinally elongated slot 41 into which extends a pin 42 on the dogging member 35.

When the arm 39 is moved to the left (Fig. 7) the dogging member 35 is positively actuated into the path of movement of the lug 23^b so that manipulation of the roll back is prevented. By rocking the arm 39 to the right the dogging member 35 is first withdrawn from latching position and thereafter the abutment 38 is moved into engagement with the lug 34 on the bolt so as to reTRACT the bolt.

Figures 10 and 11 show a latch similar to that shown in Figs. 7 to 9, but instead of employing an arm 39, a lever arm 43 is provided for reTRACTING the bolt and actuating the dogging member to and from latching.

position. The lever arm 43 is vertically disposed and is pivoted at its lower end to a stud 44 on the back plate. The upper part of the lever arm projects outwardly from the back plate so as to be grasped for operation. Similar to the arm 39 the lever arm 43 is provided with a vertically elongated slot 41^a into which a pin on the dogging member projects. For holding the lever arm in neutral position and prevent rattling, a leaf spring 45 is fixed at 46 to the top plate 47 and engages the arm 43 through a slot 48.

In each of the described embodiments of the invention, there is shown a sliding pawl or dog which is movable in a plane parallel to the plane of movement of the bolt. The pawl, when in operative position, prevents manipulation of the roll back, or outside retracting means and this member is moved to such position by rocking movement of the main operating means in a direction opposite to the direction of movement employed for withdrawing the bolt. Attention is also drawn to the feature by which the dogging member is moved away from latching position in the same direction as the bolt by no special manipulation of the main controlling lever or shaft, the dogging member being first retracted and subsequently the bolt.

While I have described my construction in more or less detail to comply with the requirements of the statute, it is nevertheless desired that this detailed description be considered merely as illustrative, and not as limiting, and it is to be understood that changes and modifications may be made by those skilled in this art without departing from the invention as defined in the following claims.

What I claim as new and desire to secure by Letters Patent is:

1. In a door latch, the combination of a spring-pressed bolt, means on the inside of the door for retracting said bolt, a roll back, a slideable dogging member for said roll back guided on said bolt, and means for actuating said dogging member.

2. In a door latch, the combination of a spring-pressed bolt, means on the outside of the door for retracting said bolt, a roll back for said bolt, a dogging member slideable on said bolt and movable into the path of movement of said roll back, and an operative connection between said inside operating means and said dogging member whereby retracting movement of said inside retracting means withdraws said dogging member before retracting said bolt.

3. In a door latch, in combination with a tensioned bolt, means operable from the inside of the door for retracting the bolt, means operable from the outside of the door for retracting the bolt, slideable means for dogging said outside retracting means, and means between said inside retracting means and the slideable means whereby retracting movement

of the inside means first retracts said slideable means and subsequently retracts the bolt.

4. In a door latch, in combination with a spring tensioned bolt, means operable from the outside of the door for retracting the bolt, means operable from the inside of the door for retracting the bolt, a link between the bolt and said inside retracting means, a lost-motion connection between said link and bolt, a slideable dogging member for said outside retracting means, and a lost-motion connection between said dogging member and link whereby retracting movement of the inside means first retracts the dogging member and subsequently retracts the bolt.

5. The combination with a latch bolt, of a spring normally projecting said bolt, outside means for retracting said bolt, inside means for retracting said bolt comprising a reciprocable handle having a normal position at an intermediate point in its path, and means operated by the handle during its reciprocation from normal position through one end of its path to retract the bolt and allow full projection of the bolt, and a slideable dog operated by the handle during its reciprocation from normal position through the other end of its path to dog and release said outside means while the bolt remains in fully projected position.

6. The combination with a latch bolt, of a spring normally projecting said bolt, outside means for retracting said bolt, inside means for retracting said bolt comprising a reciprocable handle having a normal position at an intermediate point in its path, a dog, and connections between the handle, bolt and dog for retracting the bolt and allowing full projection thereof during the reciprocation of the handle from normal position through one end of its path and for positively moving the dog to dogging position during movement of the handle from normal position to the other end of its path and positively returning the dog to releasing position when the handle is returned to normal position.

7. The combination with a latch bolt, of a spring normally projecting said bolt, outside means for retracting said bolt, inside means for retracting said bolt comprising a reciprocable handle having a normal position at an intermediate point in its path, a rectilinearly reciprocating dog, and connections between the handle, bolt and dog for retracting the bolt and allowing full projection thereof during the reciprocation of the handle from normal position through one end of its path and for positively moving the dog to dogging position during movement of the handle from normal position to the other end of its path and positively returning the dog to releasing position when the handle is returned to normal position.

8. In a remote control latch, the combina-

tion of a latch unit including a tensioned bolt, an outside controlled roll back rotatable for retracting said bolt, a remote control unit for retracting said bolt including a reciprocating handle having a normal position at an intermediate point in its path, and a connection between said handle and bolt, said connection comprising a link and a lost motion connection with said bolt enabling retraction of said bolt and full projection thereof in one end of the handle movement from normal position, and allowing lost motion of said handle in the other end of the handle movement, a slidable dog for directly blocking said roll back by movement into the path of the same, and a connection between said dog and link for positively sliding said dog to and from roll back-blocking position upon said lost motion movement of said handle.

9. In a door latch, the combination of a back plate having a flange, a latch bolt projectable through said flange to latching position, spring means urging said latch bolt to projected latching position, a roll back at one side of said bolt, a projection from said bolt in position to be engaged by said roll back, a dog rectilinearly slidable in the direction of the movement of said bolt, and inside operated means for actuating said dog and reTRACTING said bolt, said means comprising an operating plate, a pin and slot connection between said operating plate and bolt, the slots running in the direction of movement of the bolt, means connecting said operating plate to a remote control, and connections between said operating plate and dog moving said dog into position to dog said roll back when the operating plate is moved toward said flange after the bolt is fully projected and during relative movement of said pin and slot and for retracting the dog from dogging position when the plate is moved away from the flange to engage the pin with the end of the slot for bolt retraction.

10. In a door latch, in combination with a tensioned bolt, means operable from the inside of the door for retracting the bolt, means operable from the outside of the door for retracting the bolt, slidable means for dogging said outside retracting means and means between said inside retracting means and the slidable means whereby retracting movement of the inside means first retracts said slidable means and subsequently retracts the bolt, said last named means including an operative connection between said inside means and sliding means whereby movement of the inside retracting means in a non-bolt-retracting direction positively moves said dog to dogging position.

11. In a door latch, in combination with a tensioned bolt, means operable from the outside for retracting said bolt, slidable means for dogging said outside retracting means, means operable from the inside of the door

for retracting said bolt, said inside means comprising a reciprocating handle having a normal position at an intermediate point in its path, means between said inside retracting means and the said slidable dogging means including a link and lost motion connection with said bolt enabling retraction and full projection thereof in one end of the handle movement, and allowing lost motion of said handle, relative to said bolt, in the other end of the handle movement for positively moving said dog to dogging position while said bolt is fully projected, and for retracting said dog whereby retracting movement of the inside handle first retracts the slidable dogging means and subsequently retracts the bolt.

12. In a door latch, the combination with a tensioned latch bolt, of means operable from the outside of the door for retracting the bolt, means operable from the inside of the door for retracting the bolt, said means being mounted at a point distant from said outside means and for movement in opposite directions from a normal position, and a connection between said inside means and bolt compelling retraction of the latter on movement of said inside means in one of its directions, said connection including a slidable bar movable in the direction of movement of said bolt, a dogging lug operatively connected to the forward end of said bar engagable directly with said outside means upon movement of said inside means in its opposite direction, and a pin and slot connection between said bar and bolt affording lost motion of said bar relative to said bolt, whereby retracting movement of the inside means first retracts said bar and dogging lug and subsequently retracts the bolt.

13. In a door latch, a back plate, a tensioned latch bolt movable over said back plate, outside operated means for retracting said bolt, inside operated handle for retracting said bolt, a pair of contact surfaces on said bolt spaced longitudinally thereof, a single element having a portion movable between said contact surfaces, a portion of said element being movable into and out of blocking engagement with said outside retracting means while the bolt is fully projected, and means for operating said element from the inside operated handle.

14. In a door latch, a back plate, a tensioned latch bolt movable over said back plate, outside operated means for retracting said bolt, an inside operated handle for retracting said bolt, a pair of contact surfaces on said bolt spaced longitudinally thereof, a single element having a portion movable between said contact surfaces, a portion of said element being movable into and out of blocking engagement with said outside retracting means while the bolt is fully pro-

jected, said element being movable rearwardly a distance sufficient to retract the bolt by engagement with the rear abutment, and means for operating said element from the 5 inside operated handle.

15. The combination with a latch bolt, of a spring normally projecting said bolt, outside means for retracting said bolt, inside means for retracting said bolt comprising a recip-

10 roitable handle having a normal position at an intermediate point in its path, a reciprocating dog, and means operated by the handle for retracting the bolt and allowing full projection thereof during the reciprocation

15 of the handle from normal position through one end of its path and for positively moving the dog to dogging position during movement of the handle from normal position to the other end of its path and positively re-

20 turning the dog to releasing position when the handle is returned to normal position.

16. A door latch comprising a back plate, a spring tensioned latch bolt on said back plate, an outside retractor including a roll back for 25 withdrawing said bolt, an inside retractor for said bolt including a single element having a lost motion connection with said bolt for retracting the same, and movable to another position into direct engagement with said roll

30 back to render the latter inoperative.

17. In a remote control latch, the combination of a latch unit, a bolt slidably supported by said unit, a separate remote control unit including an operating handle, an outside re-

35 tractor for said bolt mounted on the latch unit, rectilinearly slidable means for dogging said retractor mounted on the latch unit, an inside operated plate secured on the latch unit, a mounting for said plate affording lost

40 motion thereof relative to said bolt when the latter is in projected or latching position, a connection between said dogging means and plate for moving said dogging means to dog and release said outside retractor when the

45 bolt is projected, and means connecting the plate and the operating handle on the remote control unit.

In testimony whereof I have hereunto signed my name to this specification.

50 FLETCHER D. GRUND.
